SHOE

Pearl Y. Smiley, Kitchener, Ontario, Canada, assignor to The B. F. Goodrich Company, New York, N. Y., a corporation of New York

Application April 4, 1936, Serial No. 72,725

4 Claims. (Cl. 36—7.3)

This invention relates to shoes having a fur trimming about the top of the upper.

Heretofore shoes have been provided with fur around the margin of the upper. Such fur trimming has been doubled in V-shape about the margins and sewed thereto. It has been found that such fur trimmings become compressed between the shoe and the limb, causing the fur to become matted and worn. When the fur becomes wet it soils the stockings of the wearer due to contact therewith. When the wearer attempts to draw the shoe onto the foot the unprotected and inadequately supported fur is often grasped and pulled from the shoe.

The principal objects of this invention are to provide a structure and method of constructing such shoes which will overcome these disadvantages, and to provide simplicity of construction.

Other objects will appear from the following description and the accompanying drawing.

Of the drawing:

Fig. 1 is a perspective view of the completed shoe in its preferred form.

Fig. 2 is a sectional view taken on line 2—2 of Fig. 1, the lower portion of the shoe being broken away.

Fig. 3 is a fragmentary sectional view taken on line 3—3 of Fig. 2.

Referring to the drawing, the numeral 10 designates the fabric outer covering of the shoe, the numeral 11 a layer of rubber, and the numeral 12 the fabric lining. These three layers are vulcanized together throughout the upper of the shoe except above the line 13, above which the outer covering 10 is separated from the other components of the upper. Above the line of separation 13, a layer 14 of fabric is applied to the layer of rubber 11. The fur edging 15 is stitched to the upper edge of the covering 10 as at 16, the fur strip being doubled over the upper edge of the covering.

In order to shield the fur from contact with the stocking, the plies 11, 12, and 14 are extended above the fur-trimmed covering 10, and a binding 17 is applied thereto. This construction is continued along the edges of the vent in front of the shoe in a modified form, the fur being applied about the edge of the outer covering and the outer covering being attached to the other layers of the upper by a line of stitching 18.

By this construction, the fur is deflected away from the limb so as to prevent contact of the fur with the stocking. The extension of the upper beyond its outer covering provides a gripping element by which the shoe may be drawn onto the foot without loosening the fur.

I claim:

1. In an overshoe, including an outside member and an inner lining forming parts of the upper; a trimming strip of fur stitched to the inside of the upper by a row of stitching passing through the outside member adjacent the upper edges of the same, said strip being folded to lie over the upper edges of said outside member and to extend down along the outside member, a second row of stitching passing through said outside member adjacent the lower edge of said fur strip, said inner lining projecting above the upper stitched portion of the fur strip for purposes described.

2. An article of footwear comprising a sole, an upper attached thereto and having a facing and a lining secured to each other near the sole but unattached over an area adjacent their free margins and an ornamental trimming attached over the free margin of the facing, the unattached portion of the lining extending between the trimming and the limb of the wearer so as to protect the stocking from contact with the trimming and terminating short of the top of the trimming so as to be concealed thereby.

3. An article of footwear comprising a sole, an upper attached thereto and having a facing and a lining secured to each other near the sole but unattached adjacent their free top margins, and an ornamental trimming attached over the free top margin of the facing, the unattached portion of the lining extending upwardly between the trimming and the limb of the wearer so as to protect the stocking from contact with the trimming and terminating below the top of the trimming so as to be concealed by the trimming.

4. An article of footwear comprising a facing and a lining forming part of the upper, a trimming strip of fur-like material attached to the inside of the facing, said strip being folded over the upper margin of the facing and being secured thereover, said lining projecting above the bottom of the trimming strip but terminating below its fold.
